(57) **CLAIM**

We claim the ornamental design for a digital media device, as shown and described.

DESCRIPTION

FIG. 1 is a front elevational view of a digital media device showing our new design;

FIG. 2 is a top plan view thereof;

FIG. 3 is a right side elevational view thereof, the left side elevational view being a mirror image thereof;

FIG. 4 is rear elevational view thereof; and,

FIG. 5 is a bottom plan view thereof.

The broken lines are for illustrative purpose only and form no part of the claimed design.
